UNITED STATES PATENT OFFICE

JACOB KULLMAN, OF HILLSBOROUGH, CALIFORNIA

ACOUSTICAL DEVICE

Application filed June 14, 1929. Serial No. 370,814.

This invention relates generally to acoustical devices in which mechanical vibrations are translated into sound. It has particular application to the construction of devices 5 excited with electrical current variations of voice frequencies, such as loud speakers.

It is a general object of the present invention to devise a loud speaker or equivalent device which will give substantially faithful 10 reproduction of voice or musical frequencies.

It is a further object of this invention to devise a novel form of sound baffle for use in combination with an acoustical device, such 15 as a loud speaker reproducing unit, which will increase the quality of reproduction and will make the tones more pleasing.

Further objects of the invention will appear from the following description in which 20 I have set forth the preferred embodiment of my invention. It is to be understood that the appended claims are to be accorded a range of equivalents consistent with the state of the prior art.

25 Referring to the drawing:

Figure 1 is a side elevational view in cross section, illustrating a device constructed in accordance with my invention.

Fig. 2 is a front view of a portion of the 30 device shown in Fig. 1.

Fig. 3 is a side elevation in cross section, illustrating a modification of my device.

Fig. 4 is a front elevational view showing 35 a portion of the device shown in Fig. 3.

In loud speakers which have been used in the past, it has been found desirable to employ baffles in conjunction with sound reproducing units, in order to secure proper reproduction of the lower tones. For example in a loud 40 speaker of the type utilizing a tympanum or other form of diaphragm vibrated mechanically by a magnetic driving unit, the baffle extends outwardly for a substantial distance from the periphery of the tympanum. If the 45 magnetic unit is mounted within a cabinet, as for example in the cabinet of a radio receiving set, the front and side walls of the cabinet form the required baffle. Baffles which have been used in the past have been constructed of wood, pressed fibre, or equivalent

material. In developing loud speakers which will give superior quality of reproduction, I have discovered that the tones produced by a given reproduction unit can be materially influenced by utilizing hide in place of wood or pressed fibre for the baffle construction. 55 By comparative test I have found that a loud speaker having a hide baffle will reproduce tones over the entire voice frequency range more faithfully and of better quality, the shrill and harsh tones generally reproduced by a loud speaker are minimized, and the general tonal effect is more pleasing.

Referring to the drawing for one specific form of my invention, in Figs. 1 and 2 I have 60 shown a conical diaphragm or tympanum 10 in conjunction with a magnetic driving device 11. Device 11 may be of the dynamic type 65 in which a coil 12 is secured to the apex of cone 10 and operates within an annular magnetic gap. A permanent magnetic field can be provided, or device 11 can have a field winding connected to a suitable source of current. Electrical current variations of voice 70 frequencies, as for example that obtained 75 from the output of a radio receiving set, are impressed upon the coil 12. The inner portion of the cone 10 is shown resiliently supported by means of spring strips 13, while the periphery is resiliently supported by a 80 flexible edge portion 14. A suitable rigid frame 16, carried by the magnetic device 11, serves as a support for the flexible edge portion 14. The baffle which is used in conjunction 85 with tympanum 10, is formed by one or more pieces of hide 17 supported by a suitable frame. The frame in this instance consists of an outer structure 18 serving as a 90 support for the outer peripheral edge of the hide, and an inner structure 19 which terminates the inner edge of the hide near the outer periphery of the tympanum 10. Frame 18 can be supported in any suitable manner on a cabinet or other mounting for the loud speaker, or if desired, hide 21 and frame 18 95 can be supported by each other and both carried by inner frame 19. The hide is preferably stretched upon the frame with considerable tension. The extent of the baffle from the peripheral edge of the tympanum should 100

be sufficient to insure proper reproduction of the low tones. Since the minimum dimension requirements for acoustical baffles of this kind are well known in the art, this matter need not be explained in detail.

5 I have found that the hides may be cured or uncured, although for strength and ease in manufacture, it is preferably cured. It is also possible to use the hide with or without the natural hide hair. The hide without hair has been found to be of marked advantage over bafile materials which have been used in the past, although best results have been secured by utilizing hide having its hair upon one surface of the same, as indicated at 21. The exact manner in which the layer of hair contributes to the success of my invention is not clear. Probably the hair entraps a layer of cushioning air in front of the baffle, and the individual hairs in following the movements of the air particles probably exerts a damping action. If the damping action actually occurs, it is not sufficient to cause distortion of the reproduced tones, but reduces the intensity or absorbs the relatively high frequency shrill tones or noises, which detract from the desired musical tones. In order that the hair upon the hide be most effective, it is preferably faced toward the front of the speaker, or towards that side of the speaker from which the sound is being propagated.

35 In Figs. 3 and 4 I have illustrated another form of baffle which is in the form of a truncated cone, rather than planar as shown in Figs. 1 and 2. In this case a metal spacing structure 24 connects together the inner and outer frame structures 118, 119 upon which the hide 117 is stretched. When positioned 40 upon the frame, the form of the hide is such that it continues the conical form of the tympanum 10. Particularly good results have been achieved with a baffle of this form made of hide, both with respect to the quality of 45 reproduction and to the propagation of the sound waves in a given direction.

I claim:

1. An acoustical device comprising a sound translating unit, and a sound baffle extending 50 over a substantial area and formed of hide having hair on one side of the same.
2. An acoustical device comprising a tympanum, magnetic means serving to vibrate said tympanum to generate sound waves, and 55 a baffle extending from the periphery of the tympanum over a substantial area, said baffle being formed of hide having hair upon its forward surface.

In testimony whereof, I have hereunto set 60 my hand.

JACOB KULLMAN.
